UNITED STATES PATENT OFFICE.

GEORGE WARNER, OF NEW HAVEN, MICHIGAN.

TOOL FOR GRIPPING AND CUTTING WIRE.

Application filed June 20, 1925. Serial No. 38,450.

This invention relates to wire working tools and more particularly to a combined gripping and cutting tool particularly adapted for use in removing the wire fastenings 5 from cement bags and the like.

The object of the present invention is to provide an improved tool of the character indicated capable of cutting the loop of such a wire fastening while at the same 10 time and with the same movement gripping the twisted parts of the fastening for pulling the same way from the bag. A further object of this invention is to provide a tool of this character so constructed that it is 15 practically impossible to injure the bag in the opening operation.

The invention consists in the novel construction, arrangement and combinations of parts as hereinafter more particularly 20 described and claimed.

One sheet of drawings accompanies this specification as part thereof, in which like reference characters indicate like parts throughout.

25 Fig. 1 is a perspective view of the improved tool applied to a sack fastening preliminary to cutting the same.

Fig. 2 is a fragmentary perspective view of the tool applied to a wire fastening loop 30 the sack being indicated in dotted lines.

Fig. 3 is a fragmentary front view of the improved tool.

Fig. 4 is a fragmentary back view of the tool.

35 In accordance with the present invention two lever members 1 are secured in pivoted crossed relation as by bolt 2. Handles 3 are provided at the ends of the longer arms of the members 1.

40 The short arm 4 of one of the members 1 is provided with a laterally directed curved flange 5 adapted to receive the short arm 6 of the other member 1. The lower edge of the short arm 4 beneath the flange 5 is provided with an arcuate notch 7 which is beveled outwardly as indicated by 8 to provide a shearing edge on the inner face of the arm 4.

45 The short arms 4 and 6 are of the same 50 length and their ends are blunt so that the tool can be forced firmly against the neck of a bag without injuring it.

In common practice cement bags are fastened by having their open end gathered

together and secured by a loop of wire 9 the 55 ends of which are twisted together as at 11. To remove this loop with my improved tool the twisted part 11 of the fastening is entered between the short arm 6 and the flange 5 and the tool forced against the neck of 60 the sack 10 until the loop part 9 of the fastening enters the arcuate groove 7 whereupon the handles 3 are drawn together forcing the short arm 6 upwardly into flange 5 gripping the twisted part 11 of the fastening 65 while at the same time the loop 9 is sheared to one side of the twisted part 11 between the shearing edge 7 and the upper edge 12 of the arm 6. In this shearing operation it will be noted that by reason of the arcu- 70 te notch 7 the loop 9 is drawn by the initial movements of the operation away from the sack thus further insuring the sack from injury. If the twisted part of the loop happens to be bent in or if the bag happens to 75 present itself to the workman with another portion of the loop toward him, it is not necessary, with this tool to seek the twisted part of the loop as it will operate efficiently on any part thereof. Where the loop proper 80 is grasped between the nippers a portion thereof is forced into the grooved flange transversely thereof and firmly gripped while at the same time the loop is severed to one side of the gripped part as will be 85 apparent from the structure of the tool.

Having thus fully described my invention, I claim:

1. A wire gripping and cutting tool comprising blunt ended pivoted members, one of 90 said members having a laterally directed curved flange adapted to receive the other member and further provided with an arcuate notch opposite said flange said notch having a shearing edge adapted to engage with 95 the upper edge of the second member.

2. A wire gripping and cutting tool comprising pivoted members having blunt ends in substantially a common plane, one of said members having a laterally directed curved flange adapted to receive the second member and further provided with an arcuate notch 100 extending from its blunt end rearwardly and on the face opposite the flange said notch having a shearing edge adapted to co- 105 operate with the upper edge of the second member.

GEORGE WARNER.
